CALENDAR CASE

Harry M. Mathers, Portland, Oreg., assignor of thirty-nine one-hundredths to Howard M. Covey, nineteen one-hundredths to Frank L. Matter, and three one-hundredths to Anna Rueger, all of Portland, Oreg.

Application September 13, 1932, Serial No. 632,908

5 Claims. (Cl. 40—110)

My invention relates to circular calendars and means for housing the same.

In my prior Patent, No. 1,874,201, August 30, 1932, I described a series of annular calendars arranged one over the other about a clock dial or similar circular space in which a pointer hand is operated to indicate the current day of the week and month, such sheets being adapted to be removed successively as each month passes.

10 The object of my present invention is to provide a practical and simple case or housing for such calendar sheets either in combination with a clock dial and clock operated calendar hand, or merely a plain dial and simple manually operated calendar hand. Such case being adapted to contain a number of such calendars either in the form of a series of sheets, the uppermost of which may be torn off and destroyed, or a series of cards of a more or less permanent nature adapted to 15 function as a perpetual calendar. One form of such case was described in my said prior patent, but not claimed and it is a further object of my present invention to provide a more practical and efficient case than that therein described.

20 A further object of my invention is to provide such a case, provided with relatively simple and practical means for holding the calendars in place and with auxiliary means adapted to hold them so that the outermost sheet is flush with the centrally located dial and thus increases its 25 visibility.

I attain my objects in a case, a hand pivotally mounted in said case, said case provided with a circumferential chamber having an open front 30 case wall substantially flush with an outer face wall of the case, said chamber adapted to hold a series of monthly calendar sheets, the said sheets having their centers cut away to permit their placement in said chamber, means for holding said calendar sheets in place in said circumferential chamber, and means for holding the sheets placed in said chamber firmly against the said outer face wall of said chamber.

These and other incidental objects and advantages of my invention and details of construction are hereinafter fully described with reference to the accompanying drawing.

In the drawing:

50 Fig. 1 shows an elevation of my case and illustrates a clock mounted within the case and the annular monthly calendar sheet in its circumferential recess;

55 Fig. 2 shows a side elevation of the same partly in section and illustrates how the monthly cal-

endars are arranged in said circumferential recess and the means for holding them in place;

Fig. 3 shows a perspective view similar to Fig. 1 except that the annular calendars and the flanged collar for holding the calendars in place at their inner margins have been removed, to show further details of construction; 5

Fig. 4 shows a detached view of the removable flanged collar adapted to be mounted over said case; and 10

Fig. 5 shows a perspective view of two of the annular calendars removed from the case.

Referring now to the figures: I have illustrated one embodiment of my invention comprising a case *a* provided with a circumferential base plate *b*, the case including an annular outstanding flange *c*. A clock *d* may be mounted in the case *a* as illustrated in Figs. 1 and 3, if desired; or a plain dial, not shown, may be used instead. 15

The case *a* is adapted to have a series of annular, monthly calendars *e* of thin paper sheets or more or less stiff cards, see Fig. 5, mounted thereon and arranged concentrically about said dial. 20

If a clock is mounted within the case *a*, a clock-operated calendar hand *f* for indicating the current day on the monthly calendars may be very readily provided, or if a plain dial is used a centrally pivoted, manually operated calendar hand will then be provided. 25

The monthly calendars *e* may either be of the kind shown in Fig. 5, in which the first days of the months are arranged at the top, one over the other; or of the kind illustrated in my said prior patent in which the first days of the month 30 of the underlying sheets are arranged to follow directly, respectively, the last day of the overlying sheet; whereby upon the removal of the overlying calendar sheet, the first day of the underlying sheet will follow directly; and the calendar hand *f*, when clock-operated, will move successively from the last day of the preceding month to the first day of the succeeding month. 35

Of course, when monthly calendars of the kind here illustrated are used, the hand *f* will have to be manually advanced over the intervening blank spaces *a'*, as in February and the months having 30 days. However, this only occurs five times during the year, namely, on the last days of February, April, June, September and November. 40

A collar *g* is adapted to be removably mounted on the flange *c*, and has an exterior shoulder *h* adapted to bear against the inner margins of the calendars *e* and hold them in place at the center. A frame *i* is also provided preferably hinged 45

55

to the base plate as at *j*, and is provided with an interior flange or shoulder *k* adapted to bear upon the outer margins of the said calendars *e* to hold them in place. The frame *i* also serves to protect the outer edges of the calendars from wear, and provides means for supporting a transparent cover, if desirable.

The collar *g* with its flange *h*, and the frame *i* with its flange *k* constitute together with annular plate *m* an annular chamber in which to place the stack of calendars *e*.

In order to provide means for holding the calendars flush against the shoulders *h*, *k*, I have provided flat spring members, *l* secured to the face of the base plate *b* within the area inclosed by the frame *i* and adapted to bear against an annular plate *m*, which serves as a backing for the calendars and presses and holds them against the said shoulders *h*, *k* so that the outermost sheet will be substantially in the plane of the calendar hand, thus promoting the visibility of the calendars and holding them snugly in the case.

I prefer to have the monthly calendars printed on thin sheets of paper, so that a supply of one or more years may be placed in my case in their consecutive monthly order, as illustrated in Fig. 2, in which event each month it will only be necessary to open the frame *i* and tear off the old calendar sheet and advance the hand over the intervening spaces *a*, if necessary.

Further, I anticipate providing a perpetual calendar consisting of relatively stiff and durable cards with monthly calendars printed on both sides, representing all the possible combinations of the days of the week and month, including leap years that will occur. With such cards I provide an index, indicating the particular card to be used for any particular month for any given year.

Thus, with this type of calendar, at the end of each month the frame *i* will be opened and the collar *g* removed, then by reference to the said index the calendar for the present month will be selected and moved to the front.

I have illustrated and described an efficient

form of construction for carrying my invention into effect, but do not wish to be limited to the precise details of construction set forth, since these may be varied; and mere modifications of the elements of the following claims within the scope of my invention are intended to be included.

I claim:

1. A case having a circumferential, annular chamber leaving a central opening, said chamber adapted to hold a series of annular sheets, a hand pivotally mounted in said opening, and means for holding the sheets placed in said chamber flush with the front wall of said case. 10

2. A case having a circumferential, annular chamber leaving a central opening, said chamber adapted to hold a series of annular sheets, a hand pivotally mounted in said opening, said chamber having an openable section, to permit the insertion and removal of said sheets, and means for holding the sheets placed in said chamber flush with the front wall of said case. 15

3. A calendar case comprising a supporting body having a central opening, a series of calendar sheets having a registering central opening, means for mounting on said body said sheets, such means including a flange overlying the marginal surface about the central opening of said sheets, and indicating means movably mounted in said central opening of the supporting body. 20

4. In a calendar case comprising a supporting body having a central opening, means for mounting on said body a series of calendar sheets having a registering central opening, such means including a flange overlying the marginal surface about the central opening of said sheets, and indicating means movably mounted in said central opening of the supporting body. 30

5. In a calendar case comprising a supporting body having a central opening, means for mounting on said body a series of calendar sheets having a registering central opening, such means including a removable flange overlying the marginal surface about the central opening of said sheets, and indicating means movably mounted in said central opening of the supporting body. 40
